ATTORNEY

UNITED STATES PATENT OFFICE.

ORVILLE D. KIES, OF NEW YORK, N. Y.

DESIGN FOR A SEWING-MACHINE HEAD.

41,288.

Specification for Design.

Patented Apr. 4, 1911.

Application filed December 5, 1910. Serial No. 595,795. Term of patent 7 years.

To all whom it may concern:

Be it known that I, ORVILLE D. KIES, a citizen of the United States, residing in the city of New York, county of New York, and State of New York, have invented a new, original, and ornamental Design for a Sewing-Machine Head, of which the following is a specification, reference being had to the accompanying drawing, forming part thereof.

The drawing is a perspective view of a sewing machine head showing my new design.

I claim:

The ornamental design for a sewing machine head, as shown.

ORVILLE D. KIES.
